UNITED STATES PATENT OFFICE.

EDWARD C. GLEDHILL, OF GALION, OHIO.

ROAD SCRAPER.

Application filed August 16, 1923. Serial No. 657,788.

To all whom it may concern:

Be it known that I, EDWARD C. GLEDHILL, a citizen of the United States, residing at Galion, in the county of Crawford and State of Ohio, have invented certain new and useful Improvements in Road Scrapers, of which the following is a specification.

This invention relates to road scrapers and its primary object is to simplify the construction and operation without any loss of strength or efficiency. One important object of the invention is to provide a machine in which the scraper or blade may be tilted, reversed and vertically adjusted from one point so that a single operator may easily perform the several operations to bring the blade into the desired position. Another object of the invention is to provide means whereby the propelling force will be applied to the blade at the back of the same, and a further object of the invention is to provide a single member which may be variously operated to determine the position at which the blade will work, and the invention seeks to attain the stated objects through means which will be free of complicated constructions or arrangements. The several stated objects of the invention, and other objects which will appear incidentally in the course of the following description, are attained in such an apparatus as is illustrated in the accompanying drawings, and the invention resides in certain novel features which will be hereinafter first fully described and then particularly pointed out in the appended claims.

In the drawings:

Figure 1 is a side elevation of a road scraper embodying my improvements, the near wheels being omitted, and

Fig. 2 is an enlarged transverse section on the line 2—2 of Fig. 1.

In carrying out my invention, I employ a main frame consisting of parallel longitudinal channel bars 1 which are supported at their front ends upon a truck 2 mounted upon ground wheels 3 and to which is connected a draft pole or tongue 4. The rear ends of these main frame bars 1 are connected by any suitable structure and have secured thereto stirrups or hangers 5 in which the axle 6 of the rear ground wheel 7 is mounted. At or about the center of the main frame, I secure thereto a vertical frame 8 consisting of bars or standards having their upper ends turned inwardly, as

shown at 9, and connected by a bed plate 10 whereby a rigid structure is produced, and, to further strengthen the device, gusset plates 11 are secured to the lower portion 60 of the bars 8 and to the side bars 1, as clearly shown. The bed plate 10 is provided centrally with an opening through which an operating screw or threaded rod 12 may freely pass, and upon the said bed 65 plate around the screw is rigidly secured a cap or head 13 in which the hub 14 of a hand wheel 15 is swiveled. The hub 14 is internally threaded or grooved so as to engage the threads of the rod 12 whereby, if 70 the hand wheel be rotated, the said rod or screw will be caused to move vertically without rotating. The threaded rod or screw terminates at its upper end in an angular 75 stud 16 upon which is fitted a lever or turning bar 17 whereby the screw may be rotated bodily when desired. Below the bed plate 10, I mount upon the screw or rod 12 a second hand wheel 18 which also has its hub 19 internally threaded or grooved so as to engage 80 the threads of the rod whereby, if the said hand wheel be rotated, it will be caused to ride up or down upon the screw. The rod 12 extends downwardly below the frame bars 1 and its lower extremity is left smooth 85 or unthreaded, as shown at 20, straps or hangers 21 being secured to and depending below the lower extremity of the rod at the sides of the same, and through the lower ends of the said hangers is fitted a pivot 90 bolt or pin 22 having studs 23 projecting forwardly and rearwardly between its ends and between the said hangers. Pivots 95 engaged upon the studs 23 are brackets 24 which are secured to the back of the blade or moldboard 25 at the center thereof and at the upper edge of the same and also to the front end of a push bar 26. It will be readily understood that this arrangement provides a universal joint connecting the blade or moldboard and the front end of the push bar with the lower end of the screw or rod 12 so that the mold board may be tilted relative to the rod or may be caused to move vertically therewith. The connection between the rear bracket 24 and the front end 100 of the push bar 26 is effected by a pivot pin 27 inserted through the bracket and the front end of the push bar so that the moldboard may be turned pivotally relative to 105 the push bar and thereby reversed or set at any desired inclination relative to the 110

line of draft. A semi-circular locking bar 28 is secured to the rear side of the mold-board and is reinforced by braces 29 in an obvious manner, the semi-circular locking 5 bar consisting of an angle bar having its upper lateral flange 30 provided with openings 31 therethrough, through any one of which may be engaged a locking pin 32 carried by the push bar and having its lower 10 end adapted to engage a keeper 33 secured to the under side of the push bar.

At the rear end of the main frame, I secure a depending bracket 34 to the lower end of which is secured a socket member 35 and the 15 rear end of the push bar 26 is formed or equipped with a ball 36 engaged and held in said socket so that it may turn freely in all directions and thereby follow the adjusting movements of the scraper blade or mold-board. Braces 37 extend between and are secured to the lower end of the bracket 34 and the side bars 1 so that the thrust upon the bracket will be effectually resisted and the scraper blade will be pushed forward 20 over the road as the machine is drawn forward. The push bar 26 is preferably cylindrical, as shown clearly in Fig. 2, and its front end extends between guides 38 which are suspended at their upper ends upon a 25 cross bar 39 which is secured in and extends between the frame bars 1, as will be readily understood. Braces 40 are secured at their upper ends to the frame bars 1 and at their lower ends to the sides of the guides 38 so 30 that the guides will be positively held against lateral movement and will, therefore, efficiently perform their function of guiding the front end of the push bar. The lower ends of the guides are connected by a bolt 41 35 having a spacing sleeve 42 fitted around the same between the guides so that the guides will be prevented from binding upon the push bar as the same moves vertically but will effectually restrain the bar against lateral movement. The guides are preferably 40 angle bars having their inner webs disposed parallel and longitudinally of the machine so that smooth surfaces will be presented to the push bar and wear upon the same minimized. 45

The hub 19 of the hand wheel 18 is constructed with an annular external groove 43 within which is fitted a collar 44 and to the said collar is pivoted the upper end of a link 45 which extends downwardly and outwardly from the collar and has its lower end pivoted to the blade or mold board 25, as shown at 46.

Across the main frame bars 1 immediately 50 in rear of the gusset plates 11, I secure a plurality of transverse platform bars 47, and a seat 48 is carried by a standard 49 rising from some of said bars.

It is thought the operation of the scraper 55 will be readily understood. The machine

may be drawn over a road by draft animals or by a tractor as may be preferred, and the blade will, of course, be caused to travel with the main frame and will thereby reduce all projecting portions of the road surface and 70 turn the dirt thus taken up into the hollow portions of the surface so that the desired smooth crown or road will be produced. It will be readily noted that the propelling force is applied to the back of the blade in 75 my machine and I thereby provide an unobstructed area in front of the blade so that there are no elements which are liable to collect and hold the dirt and interfere with the desired easy action of the blade. Buckling 80 of the blade is more effectually resisted also by my present arrangement and the propelling force is not only applied through the front end of the push bar but is also transmitted through the semi-circle 28 and the 85 braces 29 so that it is distributed through the area of the blade. To adjust the blade vertically so that it will run at the proper depth and also to lift the same free of the ground when it is not to work, the hand wheel 15 is 90 rotated and, as this hand wheel is swiveled upon the vertical frame and, therefore, cannot move vertically, it imparts a vertical movement to the worm or screw 12 without rotating the latter. This vertical movement 95 of the element 12 is transmitted directly to the blade and the front end of the push bar so that the push bar will move vertically between the guides 38 and the blade and the parts connected therewith easily set at the desired height. The hand wheel and the threaded rod constitute a worm gear which will automatically remain in the position in 100 which it is set so that extraneous locking or braking means is not necessary in order to hold the blade in the adjusted position. To tilt the blade so as to give the desired pitch to the crown of the road, the hand wheel 18 is rotated and will be thereby caused to ride up or down upon the worm or threaded rod 105 110 115 120 125 128 130 132 134 136 138 140 142 144 146 148 150 152 154 156 158 160 162 164 166 168 170 172 174 176 178 180 182 184 186 188 190 192 194 196 198 200 202 204 206 208 210 212 214 216 218 220 222 224 226 228 230 232 234 236 238 240 242 244 246 248 250 252 254 256 258 260 262 264 266 268 270 272 274 276 278 280 282 284 286 288 290 292 294 296 298 300 302 304 306 308 310 312 314 316 318 320 322 324 326 328 330 332 334 336 338 340 342 344 346 348 350 352 354 356 358 360 362 364 366 368 370 372 374 376 378 380 382 384 386 388 390 392 394 396 398 400 402 404 406 408 410 412 414 416 418 420 422 424 426 428 430 432 434 436 438 440 442 444 446 448 450 452 454 456 458 460 462 464 466 468 470 472 474 476 478 480 482 484 486 488 490 492 494 496 498 500 502 504 506 508 510 512 514 516 518 520 522 524 526 528 530 532 534 536 538 540 542 544 546 548 550 552 554 556 558 560 562 564 566 568 570 572 574 576 578 580 582 584 586 588 590 592 594 596 598 600 602 604 606 608 610 612 614 616 618 620 622 624 626 628 630 632 634 636 638 640 642 644 646 648 650 652 654 656 658 660 662 664 666 668 670 672 674 676 678 680 682 684 686 688 690 692 694 696 698 700 702 704 706 708 710 712 714 716 718 720 722 724 726 728 730 732 734 736 738 740 742 744 746 748 750 752 754 756 758 760 762 764 766 768 770 772 774 776 778 780 782 784 786 788 790 792 794 796 798 800 802 804 806 808 810 812 814 816 818 820 822 824 826 828 830 832 834 836 838 840 842 844 846 848 850 852 854 856 858 860 862 864 866 868 870 872 874 876 878 880 882 884 886 888 890 892 894 896 898 900 902 904 906 908 910 912 914 916 918 920 922 924 926 928 930 932 934 936 938 940 942 944 946 948 950 952 954 956 958 960 962 964 966 968 970 972 974 976 978 980 982 984 986 988 990 992 994 996 998 999 1000

push bar and the flange 30 of the semi-circle 21 and the blade thereby secured in the position in which it has been set. Should the rotation of the rod 12 have effected a vertical shifting of the same, it may be returned to the proper vertical position by rotating the hand wheel 15, as will be readily understood. The vertical movement, however, due to rotation of the screw, will be so very slight that, 10 in many instances, it will be negligible and may be disregarded.

From the foregoing description, taken in connection with the accompanying drawings, it will be seen that I have provided a very simple road scraper which may be operated by one man and in which the blade may be quickly brought into any desired position and, when set, will be maintained in that position without complicated extraneous locking devices. It will also be noted that the worm screw or threaded rod 12 constitutes the main support for the blade and the dead weight of the machine is reduced through the elimination of surplus parts without 25 any loss in the strength of the machine or the durability or efficiency thereof.

Having thus described the invention, what is claimed as new is:

1. In a road scraper, the combination of 30 a main frame, a blade-supporting element mounted upon the main frame, a blade connected with the lower end of said element by a universal joint, means for rotating said element, means for effecting vertical movement of the said element, and means co-operating with said element for tilting the blade.

2. In a road scraper, the combination of 40 a main frame, a blade-supporting element carried by said frame, a blade connected with the lower end of said element by a universal joint, means for rotating said element and the blade, means for adjusting said element and the blade vertically, means co-operating with said element for tilting the blade, and a push bar having its front end pivotally connected with the blade and its rear end rotatably supported by the main frame.

3. In a road scraper, the combination of 50 a main frame, a blade-supporting element mounted thereon, a blade carried by the lower end of said element, and a single central push bar having its front end pivotally connected with the blade and its rear end supported by the main frame for universal movement.

4. In a road scraper, the combination of 60 a main frame, a rigid bracket depending from the rear end of said frame, a blade arranged in front of said bracket, a single central push bar having its rear end carried directly by said bracket and having universal movement relative thereto and its front end pivotally connected with the blade, a verti-

cally disposed blade-carrying member mounted on the main frame and having its lower end connected with the blade by a universal joint, and rigid braces secured to the main frame and to the said bracket, the 70 bracket sustaining the thrust of the push bar.

5. In a road scraper, the combination of 75 a main frame, a rigid bracket depending from the rear end of said frame, a blade arranged in front of said bracket, a single central push bar having its rear end carried directly by said bracket and having relative universal movement and its front end pivotally connected with the blade, and a vertically 80 disposed blade-carrying member mounted on the main frame and having its lower end connected with the blade by a universal joint.

6. In a road scraper, the combination of 85 a main frame, a single blade-supporting member mounted on the frame, a blade carried by the lower end of said member, a rotatable central push bar having its front end pivotally connected with the blade and 90 having its rear end supported for universal movement at the rear end of the main frame, means for tilting the blade, means for angularly adjusting the blade, and means for locking the blade to the push bar in a set 95 angular position.

7. In a road scraper, the combination of 100 a main frame, guides supported by and depending from the main frame, a single central push bar supported at its rear end by the main frame for universal movement and having its front end portion passing between said guides, a blade connected with the front end of the push bar, and means for angularly adjusting the blade.

8. In a road scraper, the combination of 105 a frame, an upright supporting bed plate at the top of the frame, a threaded blade-supporting member disposed vertically and passing freely through said bed plate, a 110 blade, a universal coupling connecting the blade at its center with the lower end of said member, and a hand wheel swiveled upon the bed plate and having an internally threaded hub engaging the threaded blade-supporting member.

9. In a road scraper, the combination of 120 a frame, a vertically disposed threaded blade-supporting member mounted freely in the frame, a blade carried by the lower end of said member, a hand wheel swiveled upon the frame and having an internally threaded hub engaging and supporting the said threaded blade-supporting member whereby said member and the blade may be 125 adjusted vertically, said member having an angular upper terminal, and a turning lever fitted upon said terminal, whereby the blade-supporting member may be rotated to effect horizontal angular adjustment of the blade. 130

10. In a road scraper, the combination of a frame, a vertically disposed threaded blade-supporting member mounted freely in the frame, a blade carried by the lower end of 5 said member, a hand wheel fitted upon the said member and having an internally threaded hub engaging the same whereby rotation of said hand wheel will effect vertical travel thereof along the blade-supporting member, a collar fitted about said hub, and a link pivoted at its upper end to said collar and at its lower end to the blade at 10 one side of the center thereof.

11. In a road scraper, the combination of a frame, a vertically disposed blade-supporting member carried by the frame, a blade, a universal coupling connecting the blade at its center with the lower end of 15 said member, means for turning said member and the blade about the longitudinal 20 axis of the member, and means associated and cooperating with said member for tilting the blade.

In testimony whereof I affix my signature.

EDWARD C. GLEDHILL. [L.S.]
